(57) **CLAIM**

The ornamental design for case for dental handpiece, as shown and described.

DESCRIPTION

FIG. 1 is a front view of the case for dental handpiece;

FIG. 2 is a right side view of the case for dental handpiece of FIG. 1;

FIG. 3 is a plan view of the case for dental handpiece of FIG. 1;

FIG. 4 is a bottom view of the case for dental handpiece of FIG. 1;

FIG. 5 is a perspective view of the case for dental handpiece of FIG. 1; and,

FIG. 6 is a perspective view of the case for dental handpiece of FIG. 1, with the cover opened.

The body and the fastener of this article are preferably made of opaque plastic, and the cover except for the fastener is preferably made of semi-transparent plastic.

The rectangular portions of the body and the cover are spaces on which labels may be affixed, and the portions are slightly hollowed.

The left side view is omitted because it is represented identically with the right side view.

The rear view is omitted because it is represented identically with the front view.
